UNITED STATES PATENT OFFICE

2,186,656

ELECTRIC EXTENSION CORD PLUG

William Lyle Roeseler, Belton, Mont.

Application August 24, 1938, Serial No. 226,568

1 Claim. (Cl. 173—361)

This invention relates to an electric extension cord plug, and has for the primary object the provision of a device of this character which is especially adapted for use with an electric output of the type employing a screw threaded socket and eliminates customary practice of screwing the plug element into and out of the socket and which may be easily inserted into the socket for efficient electrical connection without having to turn or rotate the plug in order to properly position the same for entrance in the socket as is customary with the common type of prong plug and socket therefor.

With these and other objects in view, the invention consists in certain novel features of construction, combination and arrangement of parts to be hereinafter more fully described and claimed.

For a complete understanding of my invention, reference is to be had to the accompanying drawing and following description.

In the drawing,

Figure 1 is a vertical sectional view illustrating the plug and an adapter therefor and constructed in accordance with the present invention.

Figure 2 is an end view illustrating the plug.

Figure 3 is a view showing a modified form of adapter.

Figure 4 is an end view of the adapter shown in Figure 3.

Referring in detail to the drawing, the numeral 5 indicates the plug and 6 the adapter. The plug 5 includes a cap portion 7 provided with a chamber 7' and an opening 8 to admit to said chamber 7' an electric extension cord indicated in dotted lines in Figure 2. The plug 5 further includes a plug portion 9 integrally connected with the cap portion by spaced arms 10 and a marginal flange 11 depending below said arms for engagement with the adapter 6 when the plug portion is inserted therein. The spaced arms 10 form one wall of the chamber 7'.

A conductor strip 12 is arranged centrally of the plug portion 9 and extends through the free end of the latter in the form of a headed contact 13. The contact strip 12 includes an angularly related portion 14 which extends through the side of the plug portion adjacent the cap portion and underlies one of the arms 10 and is secured to the latter by a set screw 15 also employed for connecting one of the wires of the extension cord to the contact strip 12.

An annular contact member 15' is set in a recess formed in the plug portion 9 intermediate

the ends of the latter and has connected thereto a contact strip 16, a portion of which is embedded in the plug portion 9 and another portion thereof extends outwardly from the plug portion 9 and underlies another of said arms 10 and is secured thereto by a set screw 17 which acts to connect the other wire of the extension cord to the device.

The adapter 6 includes a cylindrical shell 18 of insulating material having integral with one end an annular portion 19 defining an opening 20 to receive the plug portion 9 of the plug 5 and also provides a finger piece for the rotation of the adapter into and out of an electric output of the screw threaded socket type.

A screw threaded ferrule type contact 21 is mounted on the cylindrical portion 18 of the adapter for threading the latter into the output socket. Resilient fingers 22 are formed on the contact 21 and extend upwardly into the cylindrical portion 18 of the adapter and engage with the annular contact 15' of the plug portion 9. Thus it will be seen that the plug 5 can be easily inserted and withdrawn from the adapter without the necessity of adjusting the plug to any particular position or relation to the adapter except to arrange the plug for an endwise movement into and out of the adapter.

Referring to my modified form of the invention as shown in Figures 3 and 4, the adapter is indicated by the character 23 and may provide an electric socket for the plug 5 by having the electrical lead wires connected to the set screws 24 and 25. The adapter 23 includes a base portion 26 and a socket portion 27. The set screw 25 is located centrally of the inner end of the socket portion 27 to be engaged by the contact head 13 of the plug 5.

Spring contact fingers 28 are arranged in the socket portion 27 to engage with the annular contact 15' of the plug and one of said fingers is connected to the set screw 24 while the other finger is clamped between the socket portion 27 and the base portion 26.

It is believed that the foregoing description, when taken in connection with the drawing will fully set forth the construction and advantages of this invention to those skilled in the art to which such devices relate so that further detailed description will not be required.

What is claimed is:

An electric fixture comprising a plug including a cap portion having a chamber and an opening to permit an electric extension cord to enter said chamber and a plurality of spaced arm portions forming one wall of the chamber and a plug por-

tion integral with said arm portions, said plug portion having a bore extending through one end thereof, a contact strip extending through the bore outwardly of one end of the plug portion and through one side of said plug portion in engagement with the cap portion, a second contact strip inserted in the plug portion and extending outwardly therefrom into engagement with the cap

portion, set screws threaded through the contact strips into certain of the arm portions of the cap portion for connecting wires of the extension cord to said contact strips, and an annular contact member mounted on the plug portion and electrically connected to the second-named contact strip. 5

WILLIAM LYLE ROESELER.
